The ornamental design for a wireless communication device, as shown and described.

DESCRIPTION

FIG. 1 is a perspective view of a wireless communication device showing our new design;

FIG. 2 is a front view thereof;

FIG. 3 is a left side view thereof;

FIG. 4 is a right side view thereof;

FIG. 5 is a top view thereof;

FIG. 6 is a bottom view thereof;

FIG. 7 is a perspective view thereof in use; and,

FIG. 8 is a perspective view thereof in use.

A rear view is omitted because it is plain and unornamental and forms no part of the subject matter of the claimed design. The broken lines showing are included for the purpose of illustrating portions of the wireless communication device in all the figures and environmental structure in FIGS. 7-8 and form no part of the claimed design.
